UNITED STATES PATENT OFFICE.

CHARLES WENDELL, OF OSWEGO, NEW YORK.

DESIGN FOR A BADGE.

SPECIFICATION forming part of Design No. 25,985, dated September 8, 1896.

Application filed July 17, 1896. Serial No. 599,567. Term of patent 3½ years.

To all whom it may concern:

Be it known that I, CHARLES WENDELL, of Oswego, in the county of Oswego, in the State of New York, have invented and produced a new and original Design for Badges, of which the following, taken in connection with the accompanying drawing, is a full, clear, and exact description.

This design is specially intended for badges and analogous articles adapted to be worn; and it consists, essentially, of a central elongated panel *b*, having its sides formed segmental and parallel, and from each of said sides and in opposite directions extends a group of radiating or diverging lines *a*,

which lines and panel, taken together, are intended to represent a sheaf of grain or analogous bundle of agricultural products. Extending from the ends of the panel *b* are two irregular panels *c c*, on which panels may be made any suitable inscriptions.

What I claim is—

The design for badges herein described as set forth and shown.

In testimony whereof I have hereunto signed my name this 13th day of July, 1896.

CHARLES WENDELL. [L. S.]
